UNITED STATES PATENT OFFICE.

WILLIAM J. REGAN, OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

COUPLING-CENTERING MECHANISM.

1,218,208.

Specification of Letters Patent.

Patented Mar. 6, 1917.

Application filed August 17, 1916. Serial No. 115,466.

To all whom it may concern:

Be it known that I, WILLIAM J. REGAN, a citizen of the United States, residing at Pittsburgh, in the county of Allegheny 5 and State of Pennsylvania, have invented certain new and useful Improvements in Coupling-Centering Mechanism; and I do hereby declare the following to be a full, clear, and exact description of the invention, such as will enable others skilled in the art to which it appertains to make and use the same.

My invention relates to mechanism enabling a trainman to readily shift a laterally movable car coupler to proper position for effecting a coupling with the coupler of an adjacent car. The invention is also designed to afford means for operating the locking mechanism of a coupler.

Generally stated the invention involves, in combination with a coupler which is mounted on a railway car, so as to be capable of swinging laterally when the car passes around a curve, a fulcrum member 25 which is mounted upon the body of the car, a triangular lever which is adapted to coöperate with the fulcrum member, and means extending transversely of the car for operatively connecting the lever and the coupler, 30 preferably through the locking device by which the parts of the coupler are maintained in normal relation, the mechanism being so constructed and arranged that the trainman may shift the coupler laterally in 35 either direction when stationed at one side of the car.

In the drawings illustrating my invention, the scope whereof is pointed out in the claims;

Figure 1 is a front elevation of a laterally movable coupler and devices embodying my invention for shifting the coupler laterally.

Fig. 2 is a detail side elevation of a coupler and a portion of the mechanism for unlocking and shifting the coupler illustrated in Fig. 1.

Fig. 3 is a detail view in side elevation showing one of the fulcrum members, the 50 actuating lever and the operating bar or rod connecting the lever to the coupler.

Fig. 4 is a detail horizontal section of the outer portion or edge of one of the walls or partitions of the fulcrum member.

In the drawings, 1 indicates a coupler of 55 a well-known type that is adapted to be connected to a railway car so as to be capable of extended lateral swinging movements with respect thereto. The coupler is provided with a lock 2 and with the usual pivoted knuckle 3. The lock 2, which may be of the vertically sliding gravity type, is preferably moved to unlocked position by means of a vertically rotatable arm or lever 4 whose outer end extends into an opening 60 in the lower end of the lock. The member 4 is provided with trunnions 5 by which it is pivotally connected to a bracket 6 that is rigidly secured to the coupler. At its rear end the lock actuating member 4 is provided 65 with a pocket or recess 7 adapted to receive the upwardly extending inner ends 8 of operating bars or rods 9 that respectively extend transversely in opposite directions toward the sides of the car. When either 70 of the rods 9 is rotated in the proper direction, the lock-operating member 4 will be swung upwardly to effect an unlocking movement of the coupler lock 2, as will be readily understood. The details of construction of the parts for operating the coupler lock heretofore described are in nowise 75 essential to my invention, but are to be regarded as illustrative merely. They are more fully described in the I. H. Milliken 80 Patent No. 1,184,116, issued May 23, 1916, for a coupler release rigging. The rods 9 by which the locking mechanism of the coupler may be actuated also serve as a means whereby the operator, by pushing or 85 pulling upon either of them as occasion may require, may shift the coupler laterally to any desired position on either side of the longitudinal axis of the car without passing from one side of the car to the 90 other. The means employed for both rotating and pulling or pushing each of the laterally extending operating rods 9 involves a triangular lever 10 which is pivotally connected to the outer end of the 95 corresponding rod 9 by means of a bolt 11, the upper end 12 of said lever being 100

adapted to coöperate with a fulcrum member 13 which is secured to the body of the car.

The fulcrum member 13 is preferably provided with a plurality of vertically extending walls 14 affording a series of pockets or recesses which receive the upper end of the lever 10 when the lever is being rotated to effect lateral movement of the coupler. To minimize the possibility of the upper end of the lever 10 catching upon the outer edges of the walls or partitions 14 of the fulcrum member, such outer edges are preferably tapered or sharpened, as at 15, and for a similar purpose the upper end of the lever is preferably provided with a sharpened boss or tapering projection 16.

Brackets, such as 17, which are open on one side to permit the ready introduction of the reciprocating operating rods 9, are preferably employed to support the operating rods from the car body in such manner that they may be capable of sliding, turning, and oscillating freely. As shown in the drawings, it is preferred to form the brackets 17 integral with the corresponding fulcrum members 13. A cotter 18 may be conveniently employed as a closure for the opening in the side of the bracket to thereby maintain the rod 9 in proper assembled relation therewith.

When the coupler is to be shifted laterally from its central position the handle end of the lever 10 is grasped by the trainman and rotated forwardly and turned on the pivot bolt 11 until the upper end 12 thereof enters the middle pocket of the adjacent fulcrum member 13. After coming into operative relation with the fulcrum member the forward rotation of the lever 10 may be continued so as to impart to the adjacent laterally extending rod 9 a corresponding rotation of sufficient extent to move the lock 2 of the coupler to unlocked position and to cause the knuckle 3 to be rotated to open position, if the coupler, as is generally the case, is provided with knuckle opening mechanism. With the lever 10 maintained in engagement with the fulcrum member, the trainman pulls or pushes upon it, as the necessary direction of lateral movement of the coupler may require, the upper end 12 of the lever fulcruming upon one of the adjacent walls or partitions 14 of the fulcrum member and a corresponding pull or push being transmitted to the operating rod 9 which is connected to the lever.

Should it be necessary to shift the coupler laterally to its extreme position, or should the leverage obtained when the lever 10 extends into the middle pocket of the fulcrum member 13 be insufficient to permit the operator to shift the coupler easily to the desired position, the coupler may be shifted laterally a portion of the required distance

while the lever 10 coöperates with the middle pocket, after which the upper end 12 of the lever may be transferred to the appropriate one of the adjacent pockets of the fulcrum member, thus affording better leverage for moving the coupler farther. By reason of the character of the lever and its relation to the parts with which it coöperates, the trainman is enabled to apply much more force in pushing the coupler than could be applied with a straight lever, and at the same time the lever has practically the same efficiency as a straight lever when the trainman shifts the coupler by the application of a pulling force. It is to be noted that when the lever 10 hangs in its normal position the upper end thereof is in a position in which it cannot interfere with the pocket walls of the fulcrum member 13 during the operation of unlocking the coupler.

I claim:

1. In mechanism of the character indicated, the combination with a coupler mounted on a railway car so as to be capable of moving laterally, of means for shifting said coupler laterally in either direction, said means involving a fulcrum member, a triangular lever movable into and out of engagement with said fulcrum member, and means extending transversely of the car for operatively connecting said lever with said coupler.

2. In mechanism of the character indicated, the combination with a coupler mounted on a railway car so as to be capable of moving laterally, of a locking device for maintaining the parts of the coupler in coupled relation, means extending toward the side of the car for shifting the coupler laterally in either direction and adapted to effect an unlocking movement of said locking device, and a triangular lever connected to said means and adapted to actuate the same.

3. In mechanism of the character indicated, the combination with a coupler mounted on a railway car so as to be capable of moving laterally, of means for shifting said coupler laterally in either direction, said means involving a fulcrum member affording a plurality of fulcra, and a triangular lever adapted to coöperate with said fulcra.

4. In mechanism of the character indicated, the combination with a coupler mounted on a railway car so as to be capable of moving laterally, of means for shifting said coupler laterally, said means involving a fulcrum member, a rod operatively connected to said coupler and extending toward the side of the car, and a triangular lever movably connected between its ends to said rod and movable into and out of engagement with the fulcrum member.

5. In mechanism of the character indi-

cated, the combination with a coupler mounted on a railway car so as to be capable of moving laterally, of means for shifting said coupler laterally in either direction, 5 said means involving a fulcrum member on the car, a triangular lever, means for connecting the triangular lever with the coupler, a support for said means on which it is

movable, the triangular lever being movably connected with and supported by the means 10 which connect it with the coupler, and adapted to be moved into and out of engagement with the fulcrum member.

In testimony whereof I affix my signature.

WILLIAM J. REGAN.
